(57) **CLAIM**

The ornamental design for a pet training receiver, as shown and described.

DESCRIPTION

FIG. 1 is a front elevational view of a pet training receiver showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof; and,

FIG. 8 is a top, rear and right side perspective view thereof. The broken lines in the drawings illustrate portions of the pet training receiver which form no part of the claimed design.

1 Claim, 8 Drawing Sheets
